UNITED STATES PATENT OFFICE.

FRANK H. CATHCART, OF WASHINGTON, DISTRICT OF COLUMBIA.

ROTARY ENGINE.

SPECIFICATION forming part of Letters Patent No. 224,146, dated February 3, 1880.

Application filed June 12, 1879.

To all whom it may concern:

Be it known that I, FRANK H. CATHCART, of Washington, District of Columbia, have invented certain new and useful Improvements 5 in Rotary Engines, of which the following is a specification.

The subject of my invention is a rotary engine constructed with follower-heads revolving with the rotary piston, their edges being 10 received in annular V-grooves in the cylinder, within the heads thereof. The cylinder is preferably divided longitudinally into two or more parts, affording convenience in manufacture and permitting the cylinder to be set up 15 in contact with the revolving followers in event of wear, so as to preserve constantly steam-tight joints between the revolving follower-heads and the grooves in which they turn. The rotary piston is provided with two 20 piston-slides pressed radially outward by springs. The inner periphery of the cylinder is concentric with the shaft for about one-half of its circumference, and the ports are so disposed that the piston-slides are not subjected 25 to any considerable pressure while moving radially in and out, but sustain the main pressure of the steam while they are out to their full extent and moving around the concentric portion of the cylinder. They are pressed in 30 ward toward the shaft by direct contact of the contracted portion of the cylinder, so as to pass an abutment located midway between the steam and exhaust ports, and pressed down in contact with the periphery of the rotary piston 35 ton either by a spring or by the steam.

The invention further relates to an improved slide-valve which is operated by direct connection with a rock-shaft, as hereinafter described, so as to avoid the necessity for a valve- 40 rod working endwise through a stuffing-box.

In order that the invention may be fully understood, I will proceed to describe it with reference to the accompanying drawings, in which—

45 Figure 1 is a vertical longitudinal section of my improved engine on the line 1 1, Fig. 2. Fig. 2 is a transverse section of the same on the line 2 2, Fig. 1. Fig. 3 is a perspective view of one of the follower-heads detached.

50 C C' represent the two parts of the cylinder bolted together through lugs or flanges L L. The lower part has an interior concentric with

the shaft X, while the upper part is contracted and contains a wedge-shaped vertically-sliding abutment, B, pressed downward by one or 55 more springs, b, and located midway between the ports S S', which are respectively and interchangeably the steam and exhaust ports, according as the engine is running in one or 60 the other direction.

P represents the rotary piston turning within the cylinder C C', and mounted concentrically on the shaft X.

The piston may run with its upper part 65 nearly or quite in contact with the contracted upper portion of the interior of the cylinder, requiring but very slight motion of the sliding abutment B.

s s' are supplemental ports, connected with the main ports S S' and the interior of the cylinder, in close proximity to the sliding abutment B. 70

To the ends of the rotary piston P followers F F are fixed, either by through-bolts or by bolts H H, as shown. The inner faces of the 75 followers are beveled, as shown at f' in Figs. 1 and 3, to fit the correspondingly-beveled ends of the sliding abutment B, so that as the latter is pressed in by its spring constantly tight joints will be formed, and any wear which may 80 occur will not result in leakage.

The followers are constructed with shoulders f', to fit the inner periphery of the cylinder, and with projecting V-shaped peripheries fitting in corresponding V-grooves in the cylinder. The grooves are of greater depth than the V-shaped edges of the followers, leaving a space, as shown in Fig. 1, which is kept full of oil. The sliding pistons or piston-slides P' move radially in and out within chambers p 85 in the rotary piston, and are guided by radial grooves f in the inner faces of the followers, which grooves are accurately in line with the chambers p of the piston. One or more springs, Q, of any form, are employed for pressing the 90 piston-slides outward in contact with the inner periphery of the cylinder.

V is a valve working in a steam-chest, T, and operated by a rock-shaft, R, through the medium of an arm, r, which connects directly 100 with the top of the valve V, so as to dispense with the necessity of any sliding valve-rod or other indirect communication between the rock-shaft and the valve.

W represents the steam-supply pipe, and E the exhaust, which may be carried off in any mode or direction.

The valve V is employed for stopping, starting, and reversing the engine, the said valve and the ports in the seat being so proportioned, and arranged that when the valve is placed in its central position both steam-ports S S', will be covered, so as to stop the engine, and when it is placed at either extremity of its stroke either one or the other of the steam-ports S S' will be placed in communication with the steam-chest and the other in connection with the exhaust, so as to run the engine in either direction required.

The operation is as follows: Supposing the valve to be in the position shown in Fig. 2, the piston P will turn in the direction indicated by the arrow 1, the arrows 2 indicating the direction of the live steam and arrows 3 the direction of the exhaust. One of the piston-slides P is seen at its full extent of projection and receiving the full pressure of steam from the port S, the position of this piston-slide relatively to the piston P not having changed since it entered the concentric portion of the cylinder in passing the steam-port S. The other piston-slide has retired within the piston by contact with the contracted upper portion of the cylinder, and, reaching the abutment B, passes easily beneath the same, pressing the said abutment up slightly if there be any space between the upper side of the piston C and the middle of the contracted portion of the interior of the cylinder.

As soon as the piston-slide begins to move radially outward the supplemental steam-port s' admits steam behind it, so as to prevent the formation of a vacuum. A balanced pressure is thus applied to the opposite faces of the piston-slide while it is sliding out and until it passes the main steam-port S, when it reaches its extreme projection and becomes active in rotating the shaft, which it continues to do until it reaches the main exhaust-port S', after which it becomes inactive, the supplemental exhaust-port s' preventing any compression in advance of the piston, and causing the pressure to be equal on its opposite faces until it retires completely within the rotary piston. It will thus be seen that each piston-slide is active during one half of its revolution and inactive or underbalanced pressure during the other half, and that the supplemental ports s' have the further effect of preventing dead-centers by placing the leading face of one slide in full communication with the exhaust and the rear face of the other in full communication with the steam at the instant they are passing the main ports S S'.

The grooves f and the chambers p in the piston, within which the piston-slides work radially, being accurately in line with the steam-pressure, keep the said piston-slides in close contact with the forward faces of the said

grooves and chambers, so as to automatically pack the joints and prevent any possibility of escape of steam into the exhaust portion of the cylinder. The same effect occurs on the front face of sliding abutment B. All the moving parts being thus automatically packed, the necessity of fibrous or other packing in the joints is avoided.

The valve may be operated by a simple lever, U, as shown; or it may be connected with a link-motion or a hook-motion in the ordinary manner for reversing; or it may be connected with a cut-off, so as to cut off the steam at any desired part of the stroke or effective movement of the piston-slide, so as to work the steam expansively. Any preferred valve-gear may be used for working the steam expansively. I employ separate cut-off valves on the sides of the cylinder near the outlet of the ports S S', the valve through which steam enters being connected with the cut-off. By locating the valves close to the openings of the steam-ports on each side I dispense with the long curved steam-passages and avoid the loss of steam contained therein, and also reduce the loss by condensation.

It will be observed that the wear of the cylinder is wholly on its lower half so that said wear may be compensated for by tightening the nuts of the bolts by which the two halves of the cylinder are connected together, the lugs or flanges L L being at sufficient distance apart for this purpose and suitable packing being interposed between them, as shown at L.

Cups Y Y are employed to supply oil to the V-grooves in the cylinder, and cork Z Z to draw off said oil when necessary, so that it may be strained and reused.

Any desired lubricating material may be applied in the spaces between the rotating followers and the cylinder-heads.

Light packing-glands y y are applied on the outside of the heads around the shaft to prevent the escape of the said lubricating material.

Having thus described my invention, the following is what I claim as new therein and desire to secure by Letters Patent:

1. In a rotary engine, the followers F F, constructed with beveled faces f' f', to work in tight contact with the self-packing abutment B, and with grooves f f, to support and guide the radially-moving piston-slides P, as explained.

2. In a rotary engine, the combination of the rotary piston P, the follower-heads F F, and a cylinder, C, made in two or more parts, with V-shaped grooves for receiving the peripheries of said follower-heads, in the manner and for the purposes described.

FRANK H. CATHCART.
